Des 1036

Henry E. Russell, of New Britain, Conn.
Letters Patent, No 1036, dated Aug. 10, 1858.

The schedule referred to in these Letters Patent and making part of the same.

To all whom it may concern:

Be it known that I, Henry E. Russell, of New Britain, in the State of Connecticut, have invented or produced a new and original design for Door Lock Plates, and I do hereby declare that the following is a full, clear, and exact description of the same, reference being had to the accompanying drawing making part of this specification.

My said design to be cast in relief on the outside of a door lock plate and termed the Village lock, represents a western village girl with a bonnet in one hand and a basket in the other standing under the shade of trees, with the village church in the distance.

In the accompanying drawing a represents the outer face of a door lock cast with the design in relief, consisting of a girl b in the costume of a western village girl with her bonnet c in one hand and a basket d in the other, standing under a tree e; the village church f being represented in the back ground.

What I claim as new is the design above described and represented in the accompanying drawing cast in relief on the outer face of a door lock plate.
